UNITED STATES PATENT OFFICE.

THEODOR RALL, OF CHICAGO, ILLINOIS.

BASCULE-BRIDGE.

1,094,473.

Specification of Letters Patent. Patented Apr. 28, 1914.

Application filed June 8, 1911. Serial No. 631,936.

To all whom it may concern:

Be it known that I, THEODOR RALL, a citizen of the United States, residing in Chicago, in the county of Cook and State of Illinois, have invented certain new and useful Improvements in Bascule-Bridges, of which the following is a specification.

This invention relates to that class of bridges known as "bascule" or "lift" bridges.

The principal object of the invention is to provide simple, economical and efficient bascule bridge.

A further object of the invention is to provide a bridge of the bascule or movable type having one or more leaves each comprising a plurality of relatively movable portions, sections, or trussings so connected as to be in equilibrium in any position to which they are adapted to be moved, and to enable said relatively movable portions, trussings or elements to be automatically locked together when in lowered or closed position,—so as to form a strong cantilever span for supporting the live load on the river arm of each leaf for a two leaf bridge,—and to be automatically disconnected or unlocked as the bridge is opened or raised, all in such a manner as to dispense with the use of any locking means separate or distinct from or in addition to the elements which form the leaf or bridge or are essential parts or elements thereof; and, furthermore to so construct, arrange and connect the relatively movable upper and lower portions, sections or trussings that the dead weight of the lower section, trussing, or river-arm, will be suspended from the upper trussing by links or connecting means adapted to permanently connect said upper and lower sections or trussings and permit them to be raised and lowered and automatically locked and unlocked.

Other and further objects of the invention will appear from an examination of the drawings, and the following description and claims.

The invention consists in the features, combinations and details of construction herein described and claimed.

In the accompanying drawings, Figure 1 is a view in side elevation of a leaf of a bridge constructed in accordance with my invention and improvements, showing the relatively movable portions locked together in lowered or closed position; Fig. 1^a, a

detail view of the rack and pinion mechanism for one side of a leaf, taken on line 1^a of Fig. 1, looking in the direction of the arrow; Fig. 2, a side elevation of a leaf constructed as shown in Fig. 1, but with the relatively movable portions or sections of the leaf in unlocked and raised or open position; Fig. 3, a plan view of the leaf shown in Fig. 1; Fig. 4, a detail plan view of the interlocking portions of the upper and lower trussings, girders or leaf members in the preferred form; Fig. 5, a detail view in side elevation of the parts shown in Fig. 4; Fig. 6, a plan view of a modification of the interlocking portions or members; Fig. 7, a detail view in side elevation of the parts shown in Fig. 6; Fig. 8, a view in side elevation of a leaf of a bridge constructed in accordance with my invention, and provided with a different form of operating mechanism from that shown in Figs. 1 and 2; Fig. 9, a plan view of the mechanism shown in Fig. 8, with a portion broken away, or omitted; and Fig. 10, a detail view in transverse vertical section, taken on line 10, of Fig. 9 looking in the direction of the arrow, and showing the construction of the rack and pinion mechanism shown in Fig. 9.

In constructing a bridge in accordance with my invention and improvements, I provide one or more leaves *a*. When there are two leaves, they are, by preference, of identical construction, and the leaf of a one leaf bridge may be of the same construction as if it were to form one of the leaves of a two leaf bridge, in respect to those parts which constitute this invention. It is therefore believed to be unnecessary to describe or illustrate more than one leaf of a given type or construction, and the description and illustration of a leaf or of the construction and mode of operation and the locking and unlocking of the relatively movable members, trussings or sections of a leaf of a given type apply in all respects to each of a plurality of leaves.

Each leaf *a* is mounted upon a suitable stationary support or supports, such as piers *b* and *c*, provided with suitable trusses, girders or side-frames *d*, having, by preference, an upright *e*, a horizontal beam, chord or bottom member *f*, and one or more braces *g* and *h*, and suitable transverse beams or frame members (not shown) adapted to support a stationary roadway or flooring. These trusses, girders or side

frames *d* are adapted to support the upper or shoreward portion of the leaf and the river arm or lower portion, section, or trussing, in movable relation to each other, and are secured at their opposite ends to the respective piers in any desired manner.

Each leaf comprises two relatively movable sections, parts or main leaf portions each movably mounted on a stationary support and having trusses or girders of such dimensions and construction as to afford the required strength to enable said relatively movable sections, parts, leaf portions, or trussings to withstand the stresses and strains to which the leaf or bridge is subjected in supporting the load thereon, and is constructed, by preference substantially as follows: An upper movable main leaf portion, part or section *i* is provided, having side trusses or girders, each comprising, by preference, a top chord *i'* and a bottom chord *j* connected by suitable intermediate or web members *k* and *l* and gussets *m*, and which trusses or girders are connected by suitable transverse beams or members *m'* which may be of any desired form and arrangement. The part *i* is mounted upon a stationary support *d*, above described, by means of trunnions or pivots *n* on opposite sides of the bridge or leaf. These trunnions or pivots are adapted to pivotally support the part *i* in position to extend above the piers and outward over the river pier when the leaf or bridge is in lowered or closed position, and to permit it to swing upward and downward to open or closed position as desired. The part *i* is provided with a counter-weight *u* on its shoreward end or tail-piece. The counter-weight is adapted to counterbalance or maintain in equilibrium the connected relatively movable main leaf portions, parts or sections of the leaf or bridge, and may be in the form of a weighted framework or receptacle of any desired construction adapted to connect the side trusses or girders of the part *i*.

A lower movable main leaf-portion, section or part *o* forms a river arm, and is provided with trusses or girders each having, by preference, a top chord *p*, a bottom chord *q*, and intermediate connecting or web members *r*, *s* and *t* of suitable form and construction, said trusses or girders being connected by means of transverse beams *u* and braces *v*. This lower main leaf-portion or movable section *o* is adapted to support a floor or roadway between the trusses or girders, and which floor or roadway may be of any desired form.

The shoreward end of the lower main leaf-member or part *o* extends beneath the riverward end of the upper leaf member or pivoted trussing *i*, and is pivotally mounted upon a suitable stationary support such as the stationary trussing or girders *d* already

described, by means of trunnions *w*, in such position that the river arm projects riverward from the river pier and beyond the riverward end of the upper trussing or movable part *i* when said relatively movable upper and lower sections or trussings are in closed or lowered position.

It is desirable to provide means whereby the relatively movable upper and lower sections or parts may be permanently connected in such a manner as to be constantly in equilibrium in any position to which they are adapted to moved, and whereby the upper and lower trusses or girders so connected in movable relation to each other are adapted to automatically interlock as they are moved to lowered or closed position, and in such a manner as to be freely movable to raised or open and unlocked position. In order to accomplish this, the lower trussing or member *o*, as already suggested, is connected, at its shoreward end with a stationary support, such as the framework or trussing *d* and pier *c*, by means of trunnions *w* on opposite sides of the leaf or bridge, and which are adapted to pivotally connect such lower trussing with its stationary support so as to permit the trussing to swing upward and downward in a vertical plane to open or closed position. The upper trussing and lower trussing or river arm are operatively connected by means of a pair of struts or links *y* which are located on opposite sides of the bridge or leaf members, the lower end of each link being pivotally connected with the lower trussing by means of a pivot 2 and the upper end of each link being connected with the upper trussing by means of a pivot 3. These links or struts *y* are each, by preference, located in the same vertical plane with the corresponding side frames of the upper and lower trussings, and the side-frames of the lower trussing are each provided with a space 4 for receiving the corresponding link *y*. These spaces, shown in Fig. 3, are adapted to permit the links to swing in said spaces from the position shown in Fig. 1 to the position shown in Fig. 2, and back, as desired. The links on opposite sides of the leaf, and the corresponding side-frames, girders, or trusses of the upper and lower trussings, respectively, are thus adapted to swing in the same vertical plane and to form a strong well braced structure.

In order to provide means whereby the upper or shoreward trussing and the lower trussing or river arm are enabled to be automatically locked together, when in lowered or extended position, in such relation as to form a strong cantilever span for supporting the live load on the river arm, and whereby said upper and lower trussings are adapted to become automatically disconnect-

- ed or unlocked at the points of interlocking engagement, as the bridge is opened or raised, the upper shoreward end or portion of the lower trussing and the outer or riverward end of the upper trussing are so constructed that they move into and out of engagement with each other, and are provided at their points of engagement with interlocking portions or elements consisting, by preference, of a detent or pin 5 on each side of the upper trussing, and a socket member 6 on each side of the lower trussing in position to engage said pins or detents respectively so as to form a secure connection between the upper trussing and lower trussing adapted to support the live load upon the river arm, and to form a strong cantaliver span when the upper and lower sections of the leaf are thus connected.
- 20 A modified form of detent and socket elements is shown in Figs. 6 and 7, in which the detent 7 is built up of I-beams which engage a buffer 8 of wood or similar material, in the socket member 9. It will be readily understood that the relative positions of the detents and socket members, respectively, may be reversed.
- The means for operating the leaf or leaves of a bridge constructed as above described, or embodying the herein described invention and improvements, may be of any desired, ordinary, known or suitable form, and is here shown in connection with the type of bridge illustrated in Figs. 1, to 7 inclusive, as comprising an anchored strut or operating member comprising side arms 10 which are connected at their lower ends with a suitable stationary support by means of trunnions or pivots 11, as shown in Figs. 1, 1^a, 2 and 3 and adapted to swing in a vertical plane, each of said side arms or strut members 10 being provided with a rack 12. (See Figs. 1, 1^a, and 3.) Each upper trussing or shoreward leaf member of the bridge is provided with a pinion 13 on each side of the leaf in toothed engagement with the corresponding rack and supported and adapted to be operated by means of a shaft 14 which is journaled in suitable bearings in members 15 of the side frames of the upper trussing. Anti-friction guiding rollers or wheels 16, supported by arms or brackets 17 are located on opposite sides of each toothed rack 12 in engagement with guiding flanges 18 on opposite sides of each rack, respectively, and the arms or brackets 17 are connected with the corresponding pinion or its support, so as to keep the respective pinions in toothed engagement with the racks during the upward and downward movements of the pinions with the upper trussing or bridge member on which the pinions are mounted. The pinions are operated by suitable trains of gears 19, indicated in Fig. 3, which trains 65 of gears are operatively connected with the shaft or shafts 14, and with a suitable source of power such as motors 20, all of which are supported by the upper trussing, which is provided with a suitable platform for supporting the operating mechanism.
- A modified form of operating mechanism is shown in Figs. 8 and 9, in which operating struts or arms 21 are pivotally connected with the upper trussing comprising top chords *i* and bottom chords *j*, by means of pivots 22 mounted in suitable bearings and connecting the operating strut or arm with the upper trussing in such a manner as to permit the upper trussing and the lower member *o* to swing upward and downward into and out of interlocking engagement with each other at points provided with detents 5 and socket members 6 on said upper and lower trussings respectively, while said trussings are articulately connected by means of links *y* or other similar or equivalent connecting and operating mechanism. Racks 23 are mounted upon the upper framework of the lower trussing *o*, and are provided with lateral flanges 24 alongside of said racks and extending with the latter longitudinally of the lower trussing or leaf member. Pinions 25 are mounted upon a shaft or shafts 26 journaled in suitable bearings on the strut or struts 21, and adapted to be operatively connected by means of suitable gearing 27 with a suitable source of power of any desired form, such, for instance, as the motors 20, already described. The strut or struts 21 are adapted to support a platform 28 on or forming a part of the strut or struts and on which the motors or operating mechanism may be mounted.
- The pinions 25 are provided with guiding wheels 29 supported upon pivoted arms or brackets 30 and in engagement with the under sides of the guiding flanges 24. Said pinions, tracks, racks, flanges and guiding wheels and brackets may be of similar construction and arrangement to that shown in Fig. 1^a, which figure would serve to sufficiently illustrate the construction and arrangement of said parts, with the exception of struts 21. (See Fig. 10.)
- The word "trussing" as used in the specification and claims herein, means "trussing or girder", and the words "trussing" and "girder" are used interchangeably, each as descriptive of any element included within or covered by the definition of the other.
- I claim:
1. In a bascule bridge, the combination of a leaf comprising in its construction a plurality of relatively movable girders, a stationary support upon which said girders are pivotally mounted, links located between the riverward ends of said pivoted girders and said stationary support and pivotally connected with both girders, for connecting the girders in permanently connected mov-

able relation to each other, said girders having interlocking members integral therewith and movable automatically into and out of interlocking engagement with each other, 5 and means for moving the connected girders to raised and lowered positions, to open and close the bridge.

2. In a bascule bridge, the combination of a leaf comprising in its construction a plurality of relatively movable girders, a stationary frame upon which said girders are pivotally mounted, links located between the riverward ends of said pivoted girders and said stationary frame and pivotally connected with both girders for connecting the girders in permanently connected movable relation to each other, each of said girders having a locking member thereon and in fixed relation thereto and movable automatically into and out of locking engagement with a locking member upon the adjacent girder, and means for raising and lowering the girders, to open and close the bridge.

3. In a bascule bridge, the combination of a leaf comprising in its construction an upper girder, a lower girder, a stationary frame for pivotally supporting said upper and lower girders, upper trunnions on the stationary frame and forming supports for the upper girder, lower trunnions located between said upper trunnions and the riverward end of the upper girder and in supporting engagement with the lower girder, connecting link mechanism connected with the upper girder between the upper trunnions and the riverward end of the upper girder, and connected with the lower girder between the lower trunnions and the riverward end of the lower girder, connecting 35 the girders in movable relation to each other, a locking pin upon and in fixed relation to one of said girders, a socket member upon the adjacent girder in position to automatically engage the corresponding locking pin 40 when the girders are in lowered position, means for supporting the girders, and means for raising and lowering the girders to open and close the bridge.

4. In a bascule bridge, the combination of a leaf comprising in its construction a lower girder, an upper girder, a stationary frame for pivotally supporting said upper and lower girders, links located between the riverward ends of said pivoted girders and said stationary frame and pivotally connected with both girders at points intermediate the stationary frame and the riverward ends of said girders, respectively for connecting said girders in permanently connected movable relation to each other, locking members upon and in fixed relation to the upper and lower girders respectively,

adapted to secure said girders together in position to form a continuous cantaliver arm when in lowered position and permit the girders to move freely out of interlocking engagement in the direction of their raised positions, and means for raising and lowering the girders, to open and close the bridge.

5. In a bascule bridge, the combination of a leaf comprising in its construction lower girders, upper girders, a counter-weight supported by the upper girders, a stationary frame upon which both of said girders are pivotally supported, links located between the riverward ends of said pivoted girders and said stationary frame and pivotally connected with both girders at points intermediate the stationary frame and the riverward ends of said girders, respectively for connecting the girders in permanently connected movable relation to each other, locking members upon and in fixed relation to the upper and lower girders respectively and movable into and out of interlocking engagement with each other, said locking members being adapted to secure the girders together in lowered position, to form a continuous cantaliver arm, and means for raising and lowering the upper and lower leaf members, to open and close the bridge.

6. In a bascule bridge, the combination of a leaf comprising in its construction a lower girder, an upper girder, a stationary supporting frame provided with upper trunnions in supporting engagement with the upper girder, lower trunnions located between said upper trunnions and the riverward end of the upper girder and in supporting engagement with the lower girder, links located between the upper trunnions and the riverward end of the upper girder and pivotally connected with the upper girder and having their lower ends pivotally connected with the lower girder intermediate the lower trunnions and the riverward end of the lower girder for connecting said girders in permanently connected movable relation to each other, locking members upon and forming parts of the upper and lower girders respectively and adapted to engage and interlock with each other when the girders are in lowered position, to form a cantaliver arm, an operating strut pivotally connected with a suitable support, and rack and pinion mechanism connected with the pivoted operating strut and with the leaf, for opening and closing the bridge.

THEODOR RALL.
